DESIGN FOR A TELEPHONIC MUSIC SELECTOR APPARATUS

Ken C. Shyvers, Seattle, Wash.

Application February 12, 1941, Serial No. 98,952

Term of patent 14 years

To all whom it may concern:

Be it known that I, Ken C. Shyvers, a citizen of the United States, residing at Seattle, in the county of King and State of Washington, have invented a new, original, and ornamental Design for a Telephonic Music Selector Apparatus, of which the following is a specification, reference being made to the accompanying drawing, forming a part thereon in which

Fig. 1 is a front elevational view of a telephonic music selector apparatus embodying my new design;

Fig. 2 is a side elevational view of the same; Fig. 3 is a rear elevational view thereof; and Fig. 4 is a top plan view of the same.

I claim:

The ornamental design for a telephonic music selector apparatus, substantially as shown.

KEN C. SHYVERS.
